UNITED STATES PATENT OFFICE

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

GRINDING, REFINING, AND MIXING MACHINE

Application filed January 18, 1929. Serial No. 333,314.

This invention relates generally to improvements in the art of grinding, refining and mixing substances, and relates more specifically to improvements in the construction 5 and operation of rotary machines for treating materials such as cocoa beans, chocolate, chemicals or the like.

A general object of the invention is to provide new and useful improvements in grinding, refining and mixing machines, whereby 10 the efficiency of operation of such machines is enhanced to a maximum with the aid of relatively simple and conveniently manipulable structure.

Some of the more specific objects of the invention are as follows:—

To provide various improvements in the details of construction of and in the mode of adjusting and of operating machines of 20 the type disclosed in United States Letters Patent 1,564,427, granted December 8, 1925.

To provide an improved mounting for the movable material treating elements of grinding, refining and mixing machines, whereby 25 any desired uniform pressure may be maintained at the treating surfaces.

To provide an improved support for the wipers or wiper elements of rotary machines wherein material is subjected to a wiping action, whereby the pressure upon a plurality 30 of elements carried by a common blade, is automatically equalized.

To provide improved individual adjusting mechanisms for each of a series of treating blades of a rotary machine wherein material is subjected to the wiping action of elements associated with the blades.

To provide an improved mechanism for actuating the individual toggles for adjusting 40 a plurality of wipers of a machine of this type, wherein the actuating or adjusting mechanism is simple and compact in construction and conveniently manipulable.

To provide an improved ball and socket 45 toggle structure for effecting adjustment of

the wipers of a rotary grinding, refining and mixing machine.

To provide an improved wiper structure and means for preventing the material being treated, from hindering the effectiveness of 50 such structure during normal operation.

To provide other improvements in the details of construction of rotary grinding, refining, polishing and mixing machines.

A clear conception of several embodiments 55 of features of the invention and of the mode of constructing and of operating mechanisms built in accordance therewith, may be had by referring to the drawings accompanying and forming a part of this specification in 60 which like reference characters designate the same or similar parts in the various views.

Fig. 1 is a fragmentary partially assembled central vertical section through a grinding, refining and mixing machine. 65

Fig. 2 is a transverse vertical section through the grinding, refining and mixing machine illustrated in Fig. 1, the section being taken through the treating chamber of 70 the machine.

Fig. 3 is an enlarged fragmentary sectional view of the improved head and toggles for effecting adjustment of the wipers, the section being taken transversely of the axis of 75 the machine.

Fig. 4 is an enlarged fragmentary sectional view of the rotor and wiper adjusting mechanism, the section being taken longitudinally of the machine. 80

Fig. 5 is an enlarged part sectional end view of one of the wipers and of the supporting and adjusting mechanism associated therewith. 85

Fig. 6 is an enlarged end view of one of the wipers and of a fragment of the supporting and adjusting mechanism, showing improved means associated with the wiper carrier for preventing material from hindering the normal operation of the wiper. 90

Fig. 7 is an enlarged end view of one of 95

the wipers and of a fragment of the adjusting and supporting mechanism thereof, showing the wiper supporting blade constructed to prevent material from entering the space between the wiper blade and its support.

Fig. 8 is a fragmentary enlarged end view of a wiper provided with modified means for preventing material from entering the space directly above the wiper.

Fig. 9 is an enlarged fragmentary side elevation of one of the wipers and its support.

Fig. 10 is a fragmentary end view of a portion of one of the wiper supporting structures.

Fig. 11 is a fragmentary longitudinal section through one of the wiper supporting structures.

Fig. 12 is a fragmentary end view of another portion of the wiper structure shown in Fig. 9.

The improved grinding, refining and mixing machine illustrated in relatively assembled condition in Figs. 1 and 2, comprises a housing forming a treating chamber 7, a rotor revolvable at relatively high speed within the treating chamber 7, gearing for actuating the rotor, and mechanism for effecting adjustment of the wipers carried by the rotor from the exterior of the housing.

The housing consists of an annular casing 2 and end heads 3, 4 coacting with the casing 2, to provide the enclosed chamber 7. The casing 2 may be surrounded by a cooling or heating jacket 9, and the end heads 3, 4 are provided with feed spouts 6, 5 respectively for admitting material to be treated to the chamber 7. The end head 4 is additionally provided with a discharge opening 8 having a removable cover for effecting access to the mill interior and removal of treated material. The end head 3 is provided with an inwardly projecting conical wall 10 which provides a main bearing for supporting the rotor.

The rotor of the machine comprises a spider 18 rigidly attached to a rotary sleeve 11, which is mounted in the bearing provided by the wall 10. A scraper 19 carried by the spider 18 is movable around the wall 10 to prevent accumulation of material thereon. An annular series of levers 24 is pivotally associated with the spider 18 by means of pins 25, and each of the levers 24 is provided with laterally projecting integral supporting members 20 extending along and in close proximity to the inner surface of the casing 2. Resilient pressure plates 26 are secured to the successive members 20 and have a series of swivel blocks 40, 41 attached thereto. The blocks 40, 41 carried by the plates 26, coact with complementary similar blocks 40, 41 attached to the medial portions of resilient wiper blades 27. Removable rods 35 extend through aligned openings in the blocks

41, and thus provide detachable pivotal connections between the supporting plates 26 and the wiper blades 27. Wiper elements or grinding bars 28 are rigidly attached to the wiper blades 27 and extend longitudinally of the machine in contact with the internal cylindrical surface of the casing 2. The wiper blades 27 may also be provided with stop pins 39 which are cooperable with the resilient supporting plates 26 to limit the swinging movement of the wiper blades about the rods 35.

As shown in Fig. 6, the supporting members 20 may also be provided with a baffle or ledge member 36 disposed at the front or leading end 37 of each of the wiper blades 27, for the purpose of preventing material from entering the space between the plates 26 and the blades 27. As shown in Fig. 7, the front of leading end 38 of each wiper blade 27 may be bent inwardly toward the adjacent plate 26, for a similar purpose. As shown in Fig. 8, the supporting member 20 may be provided with a baffle member 36 and the leading end 38 of the wiper blade 27 may be bent inwardly as in Fig. 7. With the constructions disclosed in Figs. 7 and 8, the leading end 38 of each wiper blade 27 may be bent inwardly to a sufficient extent so that only one set of stop pins 39 is necessary, the leading end 38 of the blade performing the function of a stop pin at that portion of the wiper blade 27.

The adjusting mechanism for varying the pressure exerted by the wiper bars against the interior of the casing 2, comprises a series of individual toggles, one for each wiper, all of which are simultaneously manipulable from the exterior of the machine. Each of these adjusting toggles consists of a rod 22 the outer end of which has adjustable screw thread coaction with a connector 23, and the inner end of which is provided with a knob or ball 32. The connectors 23 have spherical sockets coacting with ball members 34, these ball members being rigidly attached to the inwardly extending arms of the levers 24. The balls 32 at the inner ends of the rods 22 coact with spherical sockets in the adjusting head 21, being confined within the sockets by means of retaining caps 33 which are formed to occupy minimum space circumferentially of the head 21, but which permit considerable swinging movement of the rods 22 relative to the head 21, without interference. The head 21 is rigidly attached to one end of an adjusting shaft 12 which is slidably confined within the rotor supporting sleeve 11. The shaft 12 is provided with a keyway 42 with which a spline carried by the sleeve 11, coacts so as to permit relative longitudinal motion of the sleeve 11 and shaft 12 while positively preventing relative rotation of these elements. The opposite end of the shaft 12 is of reduced diameter and is embraced by an

externally threaded sleeve 29 the ends of which coact through ball bearings 43 with spaced abutments on the shaft 12. The sleeve 29 while being fixed against rotation with the shaft 12, is adapted to be moved longitudinally together with this shaft while an adjustment is being made. A collar 30 which is held against movement longitudinally of the axis of the shaft 12 and sleeve 29, has internal screw threads coacting with the sleeve 29, and is adapted to be rotated by means of a hand wheel 31. Upon rotation of the collar 30 by means of the hand wheel 31, the sleeve 29 will be caused to travel longitudinally of its axis and to thereby move the shaft 12 and the head 21 longitudinally of the axis of the machine.

The mechanism for driving the rotor of the machine comprises a main gear 13 keyed to the sleeve 11 and meshing with a pinion 14. The pinion 14 is mounted upon a counter shaft which also carries a somewhat larger pinion 15, the pinion 15 meshing with the driving pinion 16 carried by the driving shaft 17. The shaft 17 is adapted to be driven in any suitable manner, as by a high speed electric motor.

During normal operation of the machine the material to be treated is admitted in batches through the feed spouts 5, 6, to the treating chamber 7, and the rotor of the machine is being operated through the driving gearing. The wipers carried by the rotor are adjusted to produce the desired pressure upon the material undergoing treatment, and coact with the inner surface of the casing 2 to reduce the material to a powder and to thoroughly mix the particles. The scraper 19 functions to automatically prevent accumulation of material upon the conical wall 10, and the treated charge may be removed in an obvious manner through the discharge opening 8.

When it becomes desirable to adjust the pressure upon the wipers, it is only necessary to rotate the hand wheel 31 whereupon the adjusting head 21 will be urged along the axis of the rotor and will exert a pull or a push upon the inner ends of all of the toggle rods 22, depending upon the direction of rotation of the hand wheel 31. If the head 21 is moved toward the right as indicated in Fig. 1, the rods 22 will exert a pull upon the bell crank levers 24 and will relieve the pressure upon the wipers. If the head 21 is moved toward the left as indicated in Fig. 1, the pressure upon the wipers will be increased. Each of the individual adjusting toggles may be separately adjusted by virtue of the screw threaded outer ends of the toggle rods 22 and the ball formation of the inner rod ends, to produce equal pressures upon the several wipers of the series. It should be noted that the end balls 32 of the rods 22 permit these rods

to be turned freely about their own axes, while adjustment is being effected.

The resilient plates 26 cooperating with the pivots located midway between the leading and trailing edges of the wiper blades 27, insure equalization of the pressure upon the bars 28 disposed forwardly and rearwardly of the pivots. The universal ball and socket connections at the opposite ends of the rods 22 provide a compact adjusting mechanism affording maximum leverage, and permit location of the inner ends of these rods closely adjacent to the axis of the shaft 12 while maintaining the leverage. The adjusting mechanism furthermore produces minimum obstruction at the periphery of the treating chamber 7, and the universal ball and socket connections furthermore eliminate binding of the elements due to relative tilting of the parts. The shaft 12 and the mechanism associated therewith provide simple and effective means for simultaneously and freely adjusting all of the wipers at any time, whether the machine is in operation or idle.

By providing a baffle means or a ledge member 36 as shown in Figs. 6 and 8, or distorted leading ends 38 for the wiper blades 27 as shown in Figs. 7 and 8, or both as shown in Fig. 8, objectionable entry of material to the space between the blades 26 and plates 27 may be readily avoided. The stop pins 39 also provide simple means for preventing the blades 27 from swinging beyond predetermined limits when the blades are relieved from pressure as indicated in Fig. 6, or when such swinging movement tends to occur during normal operation of the machine by virtue of the building up of material under the leading or trailing ends of the wipers. The central rods 35 and the coacting blocks 40, 41 having large bearing surfaces, provide a simple hinged joint for each wiper which may be readily dismantled by merely removing a rod 35 through the opening 8, so as to permit removal of a wiper. The entire interior of the mill is readily accessible upon removal of the end head 4, and the various parts may be conveniently assembled and removed.

It should be understood that it is not desired to limit the invention to the exact details of construction and operation herein disclosed, for obvious modifications within the scope of the claims may occur to persons skilled in the art.

It is claimed and desired to secure by Letters Patent:

1. A device of the character described comprising a blade having front and rear grinding portions, pivot means for applying pressure to said blade between said portions, and stop means for limiting the movement of said blade about said pivot means.

2. A device of the character described comprising a resilient blade having front and rear grinding portions and an intermediate

pivotal support, and means associated with said blade and cooperable with said support to limit the swinging movement of said blade about said support.

5 3. A device of the character described comprising a resilient blade having front and rear grinding portions, pressure applying means including a resilient plate spaced from said blade, a pivotal connection between said 10 blade and said plate, and stop means carried by said blade and cooperable with said plate to limit the swinging movement of said blade about said pivotal connection.

15 4. A device of the character described comprising a blade having leading and trailing grinding portions and an intermediate pivotal support, a carrier for said blade cooperating with said support and extending along said blade in spaced relation to said leading portion, and baffle means associated with said leading blade portion for preventing free ingress of material to the space between said blade and said carrier.

5. A device of the character described comprising a blade having elongated leading and trailing grinding portions and an intermediate pivotal support, a carrier for said blade cooperating with said support and extending along said blade in spaced relation to said leading portion, and an elongated baffle secured to said carrier and extending outwardly in close proximity to said leading blade portion for preventing ingress of material to the space between said blade and said carrier.

35 6. A device of the character described comprising a blade having leading and trailing grinding portions and an intermediate pivotal support, a carrier for said blade cooperating with said support and extending along 40 said blade in spaced relation to said leading portion, the leading portion of said blade being bent inwardly toward said support, and a baffle secured to said carrier and extending outwardly and cooperating with said inwardly bent blade portion to prevent ingress of 45 material to the space between said blade and said carrier.

50 7. A device of the character described comprising an annular series of wipers revolvable about a common axis, an adjusting shaft movable longitudinally of said axis, and a direct individual connection between said shaft and each of said wipers for varying the pressures thereon.

55 8. A device of the character described comprising an annular series of wipers each consisting of a resilient blade having grinding elements associated therewith, said wipers being revolvable about a common axis, a shaft
60 movable with respect to said axis for adjusting the pressures upon said blades, and a direct individual connection between said shaft and each of said blades.

9. A device of the character described comprising a blade having grinding portions

associated therewith, said blade being revolvable about an axis, a shaft movable with respect to said axis for adjusting the pressure upon said blade, and a direct connection between said shaft and said blade including a universal joint. 70

10. A device of the character described comprising a blade having grinding portions associated therewith, said blade being revolvable about an axis, a shaft movable with respect to said axis for adjusting the pressure upon said blade, and a direct connection between said shaft and said blade including a rod having universal joints at the opposite ends thereof. 75 80

11. A device of the character described comprising a blade having grinding portions associated therewith, said blade being revolvable about an axis, a shaft movable with respect to said axis for adjusting the pressure upon said blade, and a direct connection between said shaft and said blade including a rod having universal joints at the opposite ends thereof, and means for varying the distance between said joints. 90

12. A device of the character described comprising a blade having grinding elements associated therewith, said blade being revolvable about an axis, a lever revolvable about said axis and having one arm supporting said blade and another arm extending inwardly toward said axis, a shaft movable with respect to said axis, a rod pivotally associated with said shaft and extending outwardly toward said inwardly extending lever arm, and a universal connection between said rod and said arm.

13. A device of the character described comprising a blade having grinding elements associated therewith, said blade being revolvable about an axis, a lever revolvable about said axis and having one arm supporting said blade and another arm extending inwardly toward said axis, a shaft movable with respect to said axis, a rod pivotally associated with said shaft and extending outwardly toward said inwardly extending lever arm, a universal connection between said rod and said arm, and means for varying the position of said connection with respect to the adjacent end of said rod. 105 110 115

14. A device of the character described comprising an annular series of wipers each consisting of a blade and grinding elements 120 associated therewith, said wipers being revolvable about a common axis, a bell crank providing a support for each of said wipers, a shaft movable longitudinally relative to 125 said axis, an adjusting head carried by said shaft, and a rod connecting each of said bell cranks with said adjusting head, the inner end of each of said rods having a universal connection with said head.

15. A device of the character described 130

comprising a wiper revolvable about an axis and having grinding portions associated therewith, a rod for varying the pressure upon said wiper, and a connector between said wiper and said rod, said rod having adjustable screw thread coaction at one end with said connector and having a spherical opposite end formed to permit free turning of said rod during adjusting movement thereof.
